US00D535941S

(12) **United States Design Patent** (10) Patent No.: **US D535,941 S**
(45) Date of Patent: **** Jan. 30, 2007**

(54) **BATTERY CHARGER**

(75) Inventor: **Shin Miyashita**, Tokyo (JP)
(73) Assignee: **Sony Corporation**, Tokyo (JP)
(**) Term: **14 Years**
(21) Appl. No.: **29/251,502**
(22) Filed: **Jan. 10, 2006**
(51) LOC (8) Cl. **13-02**
(52) U.S. Cl. **D13/107**
(58) Field of Classification Search D13/107-110,
D13/118-119, 184; D14/251, 253, 432, 434;
320/107-115; 455/573

See application file for complete search history.
